UNITED STATES PATENT OFFICE

ARTHUR H. WEBBER, OF BOSTON, MASSACHUSETTS.

CARBURETOR.

Application filed April 13, 1920. Serial No. 372,658.

To all whom it may concern:

Be it known that I, ARTHUR H. WEBBER, a citizen of the United States, and a resident of Boston, in the county of Suffolk and State of Massachusetts, have invented a new and Improved Carburetor, of which the following is a full, clear, and exact description.

In connection with carburetors, and particularly those intended for gas engines, the fuel mixture at idling speeds is very irregular, and many means have been employed to make the mixture properly combustible but none of these means have thus far reached ideal conditions.

Usually with the engine under load, and the throttle in its most open position, the mixture is seldom the efficient mixture that the engine should receive under these conditions. Here also many means have been devised and resorted to, both manually and automatically operated to effect the proper load mixture.

With this in view I have constructed a carburetor which shall provide a more desirable "idling" adjustment, and in which the mixture, when the engine is under "load" will embody a more explosive quality, in that a better "intermediate" and "high" speed mixture is provided, and secondly, the individual particles of the same will be more thoroughly subdivided and intimately co-mingled.

Reference is had to the attached sheets of drawings as illustrating one practical embodiment of my invention, and in which drawings,

Figure 1 is a sectional side view taken through a complete carburetor constructed in accordance with my invention.

Figure 2 is a sectional end view of the same taken along the lines 2-2 of Figure 1, and

Figure 3 is an enlarged elevational view of certain details of construction employed in connection with my improved construction.

In these views the reference numeral 5 indicates the fuel inlet which communicates with a conventional float chamber 6 housing any desired type of float 7 provided with a conventional inlet controlling valve 8 the normal fuel level being indicated by the dot and dash line A-B.

Leading from the float chamber in the usual manner is the duct 9, which may be

provided with a screen 10 to prevent foreign elements from entering into the carburetor and clogging the same.

The duct provides communication between the body of the carburetor, including a housing 11 which is provided with a mixing chamber 12 upon which any desirable type of throttle valve 13 is movably positioned.

An air inlet 14 forms a part of the housing 11 and this air inlet is provided in the conventional manner with any convenient type of choke valve 15 for providing an extremely rich mixture for starting purposes.

The air inlet 14 communicates with the lower end of the mixing chamber 12, and extending within this mixing chamber in the conventional manner is any desirable type of venturi 16, which may be held in applied position by any suitable means.

It will be noted that the housing 11 is formed at any convenient point with a bore 17, which bore is in communication with the duct 9 so that fuel may enter the same. Mounted within the bore 17 is any suitable type of nozzle 18, the upper end of which terminates in a plane slightly above that of the level of the fuel maintained in the float chamber 6, and which is supplied with air by means of a passage 19 in the venturi 16, which has its upper end extending to the inner face of the venturi, this inner end being in communication with the bore 17. This construction permits of air entering through the inlet 14 and flowing through the passage 19 to a point below the nozzle 18 so as to provide a vehicle for the fuel and to permit of the production of a combustible mixture.

The bore 17 is extended beyond the nozzle 18 to a point preferably in line with the throttle valve 13. At this point a rotatable valve member is provided in the body of the housing 11 which valve conveniently includes, reference being had to Figure 3, a body portion 20 formed with an annular groove 21 in its face which groove aligns with the extended portion of the bore 17, and a passage 22 extending to and in communication with that part of the housing 11 above the throttle valve 13.

It will now be obvious that upon the valve 13 being closed, and the engine "idling" that the mixture necessary for the operation of the same will be produced by means of the nozzle 18 and the air entering through the passage 19, the completed mixture subsequently passing around the grooved por-

tion 21 of the valve 20 and through the passage 22 into the manifold.

It will be understood that a great amount of suction will be exerted within the upper portion of the bore 17 and with a view of relieving this to a certain extent, and thinning the mixture produced by the nozzle 18 and air entering through the passage 19, I conveniently provide a second passage 23 which has its upper end in communication with the mixing chamber of the housing 11, its opposite end terminating adjacent the body of the valve 20, which valve at this point is conveniently provided with a transversely extending bore 24 communicating with a groove 25 in turn communicating with the main groove 21.

It will be appreciated that the suction upon the nozzle 18 may be broken to a greater or less extent upon the body 20 of the valve being turned so as to provide communication to a greater or less extent between the transversely extending bore 24 and the groove 21, i. e. to permit of a greater or less amount of air being introduced into the mixture, which air is received from the mixing chamber 12 and the housing 11.

Now with a view of providing means which will serve to produce an efficient mixture when the engine is unloaded, it will be noted that the duct 9 is extended beyond the bore 17 of the housing 11, and terminates in communication with the second nozzle 26 centrally positioned within the housing 11, and subsequently adjacent the point of greatest constriction of the venturi 16. An opening is provided in the face of the mixing chamber 12, which opening leads into a passage 27 in communication with the lower end of the nozzle 26.

A controlling plug or any desirable type of valve 28 is positioned within the base of the nozzle 26, and adjacent the outlet of the passage 27, and this plug or valve is formed with a restricted passage as indicated at 29, for a purpose hereinafter more fully specified.

It is now to be appreciated that air will enter through the inlet 14, and when the throttle valve 13 is opened, the air drawn through the venturi 16 will cause a suction sufficient to draw fuel from the nozzle 26 to produce a mixture.

In operating, the atmosphere adjacent the greatest point of constriction of the venturi 16 will be more rarified than in the mixing chamber 12, the ratio being approximately 5 to 3. It will be understood from this that a certain portion of the mixture will enter through the opening of the passage 27 whence it will be introduced into the fuel within the nozzle 26.

From the foregoing it will be understood that the passage 27, and the metering plug will serve to primarily relieve the suction on the fuel passing through the latter plug, thereby preventing an excessive flow of fluid at high engine speeds. By virtue of the fact that the passage 27 is connected to the mixing chamber 12, and to a point intermediate the plug and spray nozzle 26, the suction on the calibrated plug can for this reason at no time exceed the suction in the mixing chamber 12 plus the fluid friction in the passage 27. Secondly, an aerating and breaking up of the fuel to a certain extent prior to its ejection from the nozzle 26 is insured so that upon the air striking the particles of the same with great velocity, a finely sub-divided mixture will be produced.

Obviously numerous modifications of structure might be resorted to without in the least departing from the scope of my claims, which read—

I claim:

A carburetor including a constant-level fuel chamber, a body providing a mixture passage, a Venturi tube forming a portion of said mixture passage, a nozzle extending to a point in said Venturi tube slightly above the normal fuel level and fed from said constant level chamber, a flow-controlling means in the passage connecting said constant level chamber and said nozzle and substantially below the fuel chamber level, and means providing a passage having its upper end communicating with the mixture passage at a point beyond the most constricted portion of the Venturi tube and its lower end communicating with the nozzle at a point between its discharge orifice and the flow-controlling means and substantially below the normal level in the fuel chamber.

ARTHUR H. WEBBER.
